UNITED STATES PATENT OFFICE.

WILLIAM S. CLARK, OF PHILADELPHIA, PENNSYLVANIA.

METHOD OF TESTING AND DISINFECTING DRAIN AND SOIL PIPES.

SPECIFICATION forming part of Letters Patent No. 404,343, dated May 28, 1889.

Application filed October 17, 1887. Serial No. 252,636. (No model.)

To all whom it may concern:

Be it known that I, WILLIAM S. CLARK, a citizen of the United States, residing at Philadelphia, in the county of Philadelphia and State of Pennsylvania, have invented certain new and useful Improvements in the Method of Disinfecting and Testing Drain and Soil Pipes; and I do hereby declare the following to be a sufficiently full, clear, and exact description thereof as to enable others skilled in the art to make and use the said invention.

This invention relates to the testing and disinfecting of drain and soil pipes, and has for its object the disinfection and deodorizing of such pipes and the detection and locating of leaks. To effect these results this invention consists in a method of partially closing the inlets and branches of such pipes and the forcing into and through them of disinfecting vapors or fumes and afterward closing the outlets and subjecting the pipes to pneumatic pressure with air containing volatile substances, which by their odor indicate the location of the leak. This invention also embraces an apparatus for conveniently and safely conducting this process or method not claimed herein, but intended to be the subject of another application for Letters Patent.

I will now proceed to fully and particularly describe the apparatus, method, and operation for conducting this process, referring in so doing to the annexed drawings, in which—

Figure 1 shows a building in vertical section, having soil and drain pipes, to which this apparatus and method are applied. Fig. 2 shows a section of a pipe end with a plug applied. Figs. 3 and 4 show the parts of the plug in section separately. Fig. 5 shows a section of the air-forcing and fumigating apparatus; and Figs. 6 and 7 show modification of the fumigating or disinfecting apparatus in vertical section.

The same letters of reference and ordinals indicate the same parts in the several figures. A represents a soil-pipe united by bell and spigot joints A', leaded and calked in the usual manner and having branches, A², for receiving drainage, and the usual trap, A³, and outlet A⁴ to the common sewer or culvert. B are stoppers inserted in the inlets A² and outlet A⁴.

The stopper B consists of a circular plug of metal, B', having a flange, B², and a cap, B³, provided with a rim, B⁴, fitting around the plug B'. A tube, B⁵, provided with a screw-thread, B⁶, is fitted into the plug B', and extends through the cap B³, where it is provided with a nut, B⁷, fitting on the screw-thread B⁶. An elastic packing ring or band of india-rubber, B⁸, fits around the plug B', between the flange B² and the rim B⁴ of the cap B³, and when the nut B⁷ is screwed against the cap B³ the rim B⁴ and flange B² can press the ring B⁸ in the direction of its axis and cause it to expand diametrically and fit and close the inlet or outlet in which it is inserted. The tube B⁵ is provided with a stop-cock or valve, B⁹, having a suitable screw-thread or other termination adapted to connect the tubes.

C is an air-pump consisting of a cylinder, C', and piston C², inlet-valve C³ and outlet-valve C⁴. The outlet-valve is provided with a stop-cock, C⁵, terminating in a two-branched tube, C⁶, one of which branches is connected with a manometer or pressure-gage, C⁷, and the other branch with a tube, C⁸, leading to one of the stop-cocks B⁹ on one of the plugs B inserted in a branch, A², of the soil-pipe A to be fumigated and tested. Connected with the inlet-valve C³ is a fumigating chamber or vessel, D, having an air-inlet, D', at the upper portion, a perforated vessel, D², filled with an absorbent material, D³—such as sponge—and a perforated tube, D⁴, leading to the branch D⁵, connected to the inlet-valve C³ of the pump C.

The perforated vessel D² is removable and can be replaced by a vessel for burning sulphur, as shown in Fig. 6, or by a vessel for holding volatile fluids, as shown in Fig. 7, instead of the saturated sponge D³.

The process of disinfecting and testing with this apparatus is as follows: The plugs B are inserted in the branches A and outlets A⁴ and the nuts B⁷ tightened, so as to expand the packing B⁸. The disinfecting-fluid is introduced in the vessel D, and air drawn through it and forced through the tube C⁸ and out of the stop-cocks B⁹, until the escaping air passing from the other stop-cocks B⁹ indicates by its odor that the disinfecting agent has reached that part. All of the stop-cocks

B⁹, except that connected with the tube C⁸, are then closed, and the pump is operated until the desired pressure is indicated by the manometer C⁷. The stop-cock C⁶ is then closed, 5 and if the manometer shows a continuance of the full pressure the pipes A are known to be tight. If, however, the pressure is shown to subside on the manometer, an examination of the pipe A will show by the odor of the 10 escaping disinfectant or fumigating vapors the location of the leak, which, being repaired, the test is repeated until the pressure remains constant on the manometer.

Having described my invention, what I 15 claim is—

The method of fumigating and testing soil-pipes, consisting of first generating air charged with disinfecting fumes or vapors in a separate vessel, next drawing air so charged through said vessel by a pump and forcing it 20 through the pipes to be tested, then closing the outlets of said pipes, and by further pumping establishing a static pressure of the air charged with vapors, substantially as set forth.

WILLIAM S. CLARK.
